UNITED STATES PATENT OFFICE.

ELLIOTT W. JONES, OF OPELIKA, ALABAMA.

CUTTER.

No. 927,247.

Specification of Letters Patent.

Patented July 6, 1909.

Application filed March 29, 1909. Serial No. 486,519.

To all whom it may concern:

Be it known that I, ELLIOTT W. JONES, a citizen of the United States, residing at Opelika, in the county of Lee and State of Alabama, have invented certain new and useful Improvements in Cutters; and I do hereby declare the following to be a full, clear, and exact description of the invention, such as will enable others skilled in the art 10 to which it appertains to make and use the same.

My invention relates to improvements in cutters and the object of my invention is to produce a simple cutting apparatus by 15 means of which meat, bread, and similar articles may be cut in slices of definite and varying thicknesses.

With this object in view, my invention consists in the construction and combinations of parts as hereinafter described and 20 claimed.

In the accompanying drawings—Figure 1 is a perspective view of my improved cutter. Fig. 2 is a top plan view of the same, 25 the operating lever being shown in section. Fig. 3 is a partial top plan view partly in section, showing the feeding means, and Figs. 4 and 5 illustrate modified forms of the operating lever.

30 *a* represents a suitable base made of any desired material such as wood, and provided with a slot *b*. The edges of the slot are preferably protected by strips of metal *c*, screwed down into the base. Near one end 35 of the slot *b* a bracket *d* is fastened to the base, which bracket extends upwardly and is provided with a pivot pin *e* on which the cutting knife *f*, having an operating handle *g*, is mounted. The upper surface of the 40 base or table is substantially flat.

h represents a sliding abutment, between which and the knife *f* the article to be cut is confined. At the rear end this abutment is provided with a downwardly bent metal 45 piece *i*, terminating at its lower end in a fork which engages a bent guide *j*, preferably made of wire. This guide has one end fastened to one side of the base and the other end fastened to another side of the base, being bent over as shown in Fig. 2 and terminating in a loop. On the other side of the base and parallel to its upper edge, is a 50 guide *k* for the feeding rack. This guide extends out beyond the base, as shown at *m*, and is then bent in the form of a right angle and attached to one side of the base, as

shown at *n*. The other end of this guide is supported by means of a bent bracket *o*, fastened to the base and to the guide *k*. It is bent outwardly as shown at *p* to permit 60 the passage of one part of the feeding rack.

q represents the feeding rack, which is made of a U-shaped bar of metal having ratchet teeth *r* and *s* facing in opposite directions, these teeth being located on the 65 edges of said rack. This rack is adapted to slide within the guide *k*, the teeth projecting forwardly from the base beyond the guide, and the side carrying the teeth *r* being adapted to slide inside the curved portion *p* 70 of the bracket *o*. This feed rack is attached to the abutment *h* by means of an angle bar *t*, secured in any suitable manner to the abutment *h* and screwed to or made integral with the rack *q*. 75

u represents the operating lever for moving the rack, which is preferably provided with a handle or projection *v*. The lower part of this lever is provided with two prongs or teeth *w* and *x*, extending therefrom in opposite directions. The lower end of the lever *u* is perforated and engages a pin 2 on a bent arm *y*, loosely pivoted on a pin 1 on the base. The lever revolves freely on this pin 2. As shown in Fig. 4, this pin 2 85 is preferably provided with a cut away portion 3, and a screw 4 is passed through the lever and into this cut away portion, so that the lever *u* may revolve freely upon the pin 2, but is prevented from being disengaged 90 from it.

In the form shown in Fig. 5, a spring 5 is attached to the guide *k* and to the lower part of the lever *u*, which spring normally keeps the projection *w* in contact with the teeth *s*. 95 6 represents a U-shaped bracket attached to the base, which limits the movement of the lever *u*.

The operation is as follows: The parts being in the position shown in Fig. 1, the 100 knife *f* is lifted and the material to be cut is placed against the abutment *h*. Then by causing the lever *u* to engage the teeth *r*, the abutment *h* may be moved, by the movement of said lever, toward the knife *f* until a 105 small portion of the material projects to the left of the knife *f*. This portion is then cut off, the knife raised, and the abutment again fed forward the desired distance, this distance being regulated by the engagement of 110 the projection *x* with the teeth *r*. This operation is repeated, the material being cut

off in successive slices until the abutment *h* has been moved close up to the knife, whereupon the lever *u* is turned so that the projection *w* engages with the teeth *s*, and the rack bar moved back into its original position, namely, until one end of the rack bar engages the loop *m* of the guide *z*.

Having thus described my invention, I claim:

10. 1. In a cutter, the combination of a slotted base, a pivoted knife, a movable abutment, a toothed rack bar for feeding said abutment in either direction, having rows of teeth projecting in opposite directions, guides for said bar, and an operating lever having projections adapted to be engaged with the teeth on the feed rack, substantially as described.
20. 2. In a cutter, means for feeding the material to be cut, consisting of a suitable support, an abutment against which said material is placed, a feed rack having two rows of teeth projecting in opposite directions, a guide for said feed rack, and a pivotally mounted operating lever adapted to be engaged with either of the sets of teeth on the feed rack, substantially as described.
30. 3. In a cutter, means for feeding the material to be cut, consisting of a movable abutment, a feed rack secured to said abutment, made U-shaped and provided with two sets of teeth extending in opposite directions, respectively, a support, a guide secured to said support and located between the tooth carrying sides of said rack, and a vibratory rotatable lever having projections adapted to be engaged with either of the sets of teeth on the feed rack, substantially as described.
40. 4. In a cutter, the combination of a suitable base, an abutment slidably mounted on said base, guides for said abutment located on two sides of said base, a feed rack secured to one end of said abutment, said feed rack being made U-shaped and having thereon two sets of teeth projecting in opposite directions, respectively, said guides extending outwardly from said base and terminating in loops, limiting the movement of said abutment in one direction, and a pivotally
5. mounted, rotatable lever provided with projections adapted to be engaged with either of said sets of teeth, as desired, substantially as described.
5. In a cutter, the combination of a slotted base, a knife pivotally mounted on said base and adapted to be moved through the slot therein, a movable abutment against which the material to be cut rests, guides for said abutment secured to two of the parallel sides of said base, said guides extending beyond one side of said base and terminating in loops, a fork attached to said abutment and engaging one of said guides, a feed rack attached to one end of said abutment and engaging the other of said guides, said feed rack being U-shaped in cross section and being provided with two sets of teeth projecting in opposite directions, and a rotatable lever pivotally mounted on said base and provided with projections adapted to be engaged with either of said sets of teeth, substantially as described.
6. In a cutter, the combination of a slotted base, a knife pivotally mounted on said base and adapted to reciprocate within the slot therein, a movable abutment adapted to slide over the surface of said base, guides for said abutment attached to two of the parallel sides of said base and extending beyond the side of said base and terminating in loops, a fork attached to one end of said abutment and engaging one of said guides, a feed rack attached to the other end of said abutment and engaging the other guide, said feed rack being U-shaped in cross section and provided with two sets of teeth projecting in opposite directions, and a rotatable lever pivotally mounted on said base, said lever being provided with projections adapted to be engaged with either of said sets of teeth, substantially as described.

In testimony whereof, I affix my signature, in presence of two witnesses.

ELLIOTT W. JONES.
